a British company

Application September 21, 1948, Serial No. 50,311
In Great Britain September 22, 1947

9 Claims. (Cl. 178—26)

1

This invention relates to telegraph apparatus for working with so-called equal length codes, and in particular, is concerned with transmitting and receiving apparatus for error-detecting or error-indicating equal length codes.

Such equal length telegraph codes, that is to say, codes in which all the characters and other signals employed consist of the same number of units, have been well known for many years and the most common of these is the five-unit code according to which each signal is represented by five units, each of which is either a "marking" or a "spacing" condition. This five-unit code is very economical as regards the number of units employed as compared, for example, with the Morse code which requires an average of about nine units per character. Largely because of this economy in units, however, the five-unit code is very liable to the transposition of characters when signals are mutilated as frequently occurs on wireless circuits. There is approximately an 80-percent chance that the mutilation of a letter will result in another letter being received. This is most objectionable when messages are sent in cipher for then, there is nothing to guide a receiving operator when such a transposition occurs.

This feature of the five-unit code of giving rise to undetectable errors has been appreciated in the past and various methods have been proposed to overcome it. These methods, in general, necessitate the use of an increased number of units per character. One method suggested consists in building up a seven-unit code having each signal consisting of a constant number of marking units and a constant number of spacing units, for example, every signal consisting of 3 marking units and 4 spacing units. In that particular case, the number of possible signals is 35 as compared with 32 in the primary five-unit code. Such a seven-unit code, however, is open to the objection that the signals have to be entirely different from and to bear no relation to those of the standard five-unit code so that conversion of signals in one code to the other has to be effected on a character basis and can only be done with complicated apparatus. Another proposal to deal with the undetectable error draw-back of the five-unit code is to employ for each signal eight units of which the first five are the units of the corresponding signal in the primary standard five-unit code to which three units are added in such a way that each signal is constituted by four marking units and four spacing units. It is clear, however, that a departure has to be made

2

from the general system for the two signals which in the five-unit code consist respectively of five marking and five spacing units since it is not possible to arrive at a four-marking four-spacing

5. signal by the addition of three units to either of those two signals; thus this scheme has the drawback that these two five-unit signals have to be converted into special eight-unit signals differing in constitution from all the others which 10. leads to complications at both ends of the telegraph circuit.

The present invention is concerned in particular with telegraph apparatus for working with error-detecting codes in which all the signals consist of

15. the same number of marking and the same number of spacing elements arranged in different sequences; in one particular example of such codes, each signal consists of three marking elements and four spacing elements.

20. According to the invention, both codes employed—the non-error-detecting primary code converted at the sending end of a circuit into the other code which is an error-detecting code and is converted back at the receiving end of the circuit—employ signals, the elements of which are divided into two groups, of which one group in each code is, in general, the same in marking and spacing permutation for each signal while the other group in the error-detecting code is determined by the permutations of both groups of the non-error-detecting code. In some cases, as will appear later, in practice signals may also be employed in which, in changing from one code to the other, the elements of the first group have to be converted.

35. It may be pointed out that the substantially perfect security which results from the use of the seven-unit and the eight-unit codes already referred to, does not arise directly from the signals being balanced as regards the numbers of marking and spacing units but from the fact that mutilation which occurs in any one signal is almost certain to consist of a change of one or more of the units of the signal from marking to spacing, or from spacing to marking and not both at the same time. Thus, the error-detecting codes which are employed in telegraph systems comprising apparatus according to the present invention are equal length codes consisting of signals no one of which can be converted into another by the change of one or more units from marking to spacing or vice-versa.

The procedure of building up the codes employed in practising the present invention may perhaps be best made clear by considering two

examples, the first of which consists in conversion of the standard five-unit telegraph code into an error-detecting code in which each signal consists of three marking elements and four spacing elements and vice-versa. In the following table, the formation in both codes of the 32 signals employed is set out, in which M represents a marking element and S, a spacing element.

Table 1

	Five-unit primary code (Standard five unit code)		Seven Unit error-detecting code		Signals
	First Group	Second Group	First Group	Second Group	
1st Series-----	MMS MSM SMM	MM SM MS SS	MMS MSM SMM SSM	SSSS SMSS SSMS SSSM	12
2nd Series-----	MSS SMS SSM	MM SM MS SS	MSS SMS SSM	MMSS SMSM SSMM SSSM	12
3rd Series-----	SSS	MM SM MS SS	SSS	MMMS SMMM MSMM MMSM	4
4th Series-----	MMM	MM SM MS SS	MSS SSM	MSMS SMSM MSMS SMSM	4
					32

It will be noted that, in both codes, the first group consists of three signal elements and in the first three series of signals, amounting to 28 signals in all, the signal elements of the first groups are the same in both codes. In the fourth series of signals which consist of four signals, the elements of the first group have to be changed in converting from one code to the other as will be explained more fully below.

In the primary five-unit code, the second group of each signal consists of two signal elements and there are four ways in which this group can be formed viz. MM, SM, MS and SS. In converting to the seven-unit code, the second group is converted into four elements in accordance with the following scheme of conversion. In the first series of signals, it will be noted that in both codes, the first group in each signal contains two marking elements so that in the second group of the signals in the seven-unit code, only one marking element is required and to represent MM, SM, MS or SS of the second group of the five-unit signals, the first, second, third and fourth element respectively of the second group in the seven-unit code is made marking.

In the second series of signals, however, in both codes, the first group of each signal contains only one marking element so that in the second group of the signals in the seven-unit code, two marking elements are required and this second group is formed in a manner similar to that in the first series except that a second marking element is made to follow immediately after the marking element which has been provided in the conversion as described above for the first series, for which purpose, the first element is regarded as following immediately the last element.

In the third series of signals, it is seen that there is no marking element in the first group in either code so that in the seven-unit code, three marking elements are required in the second group and are obtained in each instance by

adding a further marking element after the other two marking elements. In the fourth series of signals, there are three marking elements in the first group in both codes so that in the seven-unit code no marking element is required in the second group. Since this only yields one seven-unit signal (i.e. MMMSSSS) and since four are needed to complete the 32 signals corresponding to those of the five-unit code, it is arranged that in the seven-unit code, the first group is changed to MSS to form two of the signals and to SSM for the other two signals while the second group of the seven-unit signal is either MSMS or SMSM. Thus as shown in the above table, the four seven-unit signals are:

M S S	M S M S
M S S	S M S M
S S M	M S M S
S S M	S M S M

20

In the second example, the primary code is a six-unit equal length code which is converted for transmission purposes into an eight-unit error detecting code, in which each signal consists of four marking elements and four spacing elements. Signals in this error-detecting code may be reconverted into the primary six-unit code at the receiver. The following table shows how 64 different signals may be obtained in five series, the letter M in the signals representing a marking element and S a spacing element.

Table 2

35	Six-unit Primary Code		Eight-unit error-detecting code		Signals
	First Group	Second Group	First Group	Second Group	
40 1st series-----	MMMS MMSM MSMM SMMM	MM SM MS SS	MMMS MMSM MSMM SMMM	MSSS SMSS SSMS SSSM	16
45 2nd series-----	MMSS MSMS SMMS SMSM SSMM MSSM	MM SM MS SS	MMSS MSMS SMMS SMSM SSMM MSSM	MMSS SMMS SSMM MSSM	24
50 3rd series-----	MSSS SMSS SSMS SSSM	MM SM MS SS	MSSS SMSS SSMS SSSM	MMMS SMMM MSMM MMSM	16
55 4th series-----	SSSS	MM SM MS SS	SMSM SMSM MSMS SMSM	MSMS SMSM MSMS SMSM	4
60 5th series-----	MMMM	MM SM MS SS	MSSM MSMS	MSMS SMSM MSMS SMSM	4
					64

60

It will be noted again that the signals in the two codes are each divided into two groups and that in both codes, the first group consists of four signal elements; the first three series of signals amounting to 56 signals in all. The signal elements of the first group are the same in both codes as before. In the 4th series of signals, which includes four signals, and the 5th series which contains a further four signals, the elements of the first group in the primary code have to be changed in converting one code to the other, as will be explained later.

65

In the first four series, the second group of each signal in changing from the primary code to the error-detecting code, is converted respec-

75

tively into the same four elements as in Table 1 above.

As regards the first group in the 4th series, there are no marking units in the primary code so that the first group of the eight-unit code is made to contain two marking elements in each signal and the second group can then be the same as in Table 1. In the 5th series of signals, there are four marking units in the first group in the primary code which would only provide one signal in the eight-unit code, therefore the first group is changed in the eight-unit code as shown in Table 2 and the second group in that code is the same as in the 4th series.

The converting apparatus suitable for use in connection with the above two examples at the transmitting and receiving ends of a line will now be described by way of example with reference to the accompanying drawings in which—

Figure 1 is a diagram of connections of apparatus at a transmitting station for converting standard five-unit telegraph code into a seven-unit error-detecting code;

Figure 2 is a diagram of connections for receiving such signals and for re-converting them into five-unit signals;

Figure 3 is a diagram of connections of a transmitting system for converting a six-unit primary code into an eight-unit error-detecting code; and

Figure 4 is a diagram of connections of a receiving system suitable for converting signals in the eight-unit code back into the six-unit primary code.

Referring now to Figure 1, it is assumed that standard five-unit telegraph signals on a perforated tape operate any number up to five of the peckers P_a, P_b, P_c, P_d, P_e . The peckers thus operated pass through perforations in the tape simultaneously for a suitable time in each signal period, e. g., for the time of two signal units as indicated by X in Figure 1. Each pecker when thus operated, closes contacts 1, 2, thus connecting a circuit through a winding of the corresponding relay A, B, C, D or E from the positive side of the battery at 3 to earth at 4. The relays which are thus energised, are locked up through contact springs $a1 \dots e1$ and front contacts 5 thus connecting locking windings of the respective relays A . . . E from the battery at 6, through a brush B_{r2} and continuous segment 7 to earth at 8, so that the relays in question are held locked until the end of transmission of a seven-unit signal.

The first three relays A, B and C deal with the three signal elements forming the first group of a signal as shown in Table 1 above and each has seven contact springs $a1 \dots a1, b1 \dots b1$ and $c1 \dots c1$.

When the respective relays are energised, their seventh springs $a1, b1$ or $c1$ connect battery at 9 to the first three transmitting segments $S1, S2, S3$ for the seven-unit code to send marking elements for the first, second and third series of signals but the connections to battery pass through back contacts 10 of three modifying relays $M1, M2$ and $M3$ which alter the application of battery to the first three distributor segments $S1, S2, S3$ when sending one of the fourth series of signals as shown in Table 1. Then the relays $M2$ and $M3$ or the relays $M1$ and $M2$ are energised and change the appropriate two marking elements to spacing elements as required for the first group in the seven-unit code for the fourth series of signals as seen in Table 1. This result is clearly only obtained when the first

three signal elements are marks in the five-unit primary code whereupon the relays A, B and C are energised and which of the modifying relays $M1, M2$ and $M3$ are energised depends on the state of the fifth pecker relay E. In other words, this depends upon whether the last signal element in the five-unit code of the signals of the fourth series is a mark or a space, as can be followed from Table 1. If the fifth signal element is a mark, the table shows that the second and third elements in the seven-unit code should be spaces; then the relay E is energised and battery at 11 is connected through the springs $a6, b6, c6$ and their front contacts in series and through the spring $e3$ of the relay E and its front contact by way of conductor 12, through the windings of the relays $M3$ and $M2$ in series and thence to earth. The relays $M2$ and $M3$ are thus energised, breaking connection at 10 and giving spaces for the second and third signal elements on the segments $S2$ and $S3$. However, if the fifth signal element is a space, as can be seen from Table 1, the first two elements of the seven-unit signal have to be spaces and then the connection from battery at 11 goes through the back contact 13 of the relay spring $e3$ and proceeds by the conductor 14 to energise the modifying relays $M1$ and $M2$ which break circuit at 10 and alter the first and second signal elements to spaces.

The relays D, E control four supplementary relays F, G, H, K which, at their contact springs $f3, g3, h3$ and $k3$, connect battery at 15 respectively to the distributor segments $S4, S5, S6$ and $S7$. The results obtained are as follows:

If the fourth and fifth elements of the five-unit signals are both marks, the relays D and E are energised and the first supplementary relay F is energised from battery at 16, relay spring $e2$, front contact 17, relay spring $d2$, front contact 18 through the winding of relay F to earth at 19; thus relay F at its spring $f3$ connects battery to the distributor segment $S4$, consequently the fourth element of the seven-unit signals is a mark as is required, as can be seen from the first signal in each of the series in Table 1.

If, however, the fifth element of the five-unit signal is a mark but the fourth is a space, as occurs in the second signal in the five-unit code in each series in Table 1, the relay E is energised but the relay D is not energised so that the second supplementary relay G is now energised from battery at 16, springs $e2, d2$, back contact 20 and winding of relay G to earth at 21, and now the fifth element in the seven-unit code becomes a mark.

If now the fourth element in the five-unit code is a mark but the fifth is a space, corresponding to the third signal in each series in Table 1, it will be seen that the third supplementary relay H is energised from battery at 16, spring $e2$, back contact 22, spring $d3$, front contact 23 and winding of relay H to earth at 24 so that now, as is required, the sixth element in the seven-unit signal is a mark.

Yet again, if both the fourth and fifth elements of the five-unit signal are spaces, the fourth supplementary relay K is energised from battery at 16, spring $e2$, back contact 22, spring $d3$, back contact 25, winding of relay K to earth at 26 so that now the relay K at its spring $k3$ applies marking current to the seventh segment $S7$ so that the seventh signal element in the seven-unit code is now a mark.

The above four conditions complete the requirements for forming the second group of sig-

nal elements of the first series of signals in the seven-unit code, as shown in the fourth column of Table 1. If, however, the first group of the signal elements in both codes each contains only one mark, as in the second series of signals, or contains no mark as in the third series of signals, a circuit is made from battery 27 through a back contact of at least one of the third springs *a3*, *b3*, *c3* and through at least one of the second springs *a2*, *b2* and *c2* of the relays A, B and C and through the front contact of one of the springs *f1*, *g1*, *h1* and *k1* of the relays F, G, H, K to apply battery to the transmitting segment following that transmitting segment which is connected to battery by one of the springs *f3*, *g3*, *h3* or *k3*, as described above, which is in accordance with what is required for the second and third series of signals in the seven-unit code shown in Table 1. This is arranged by connecting battery at 27 to the springs *a3*, *b3* and *c3* of the relays A, B and C and connecting the back contacts 28 of those springs respectively to the springs *b2*, *c2* and *a2* of the relays B, C and A next in order, for which purpose the relay A is treated as following the relay C and, further, by connecting the back contacts 29 of the springs *a2*, *b2* and *c2* together and to the springs *f1*, *g1*, *h1* and *k1* of the supplementary relays F, G, H and K by the conductor 30. When, as in the second series of signals, only one of the relays A, B and C is energised, there is a connection from battery 27 through one of the springs *a3*, *b3* and *c3* and its back contact and one of the springs *a2*, *b2*, *c2* and its back contact 29 to the conductor 30 and thence through one of the springs *f1*, *g1*, *h1* and *k1* to the segment S5, S6, S7 or S4, following that which has already received a mark as described above.

In addition, if the first group of signal elements contains no marks, a third segment of the segments S4, S5, S6 and S7, receives a mark from battery in accordance with the third series of signals in Table 1. This is effected by connecting battery at 31 through relay spring *a5* and back contact 32, spring *b5*, its back contact 33, spring *c5* and its back contact 34 which it will be seen, is connected by a conductor 35 to the springs *f2*, *g2*, *h2*, *k2* of all the relays F, G, H, K.

In the fourth series of signals, the first group in the five-unit code is three marks which, as seen from Table 1, has to be converted to one mark followed by two spaces or two spaces followed by one mark, as determined by the fifth signal element in the primary five-unit code; that is to say, if the fifth signal element is a mark and the relay E consequently energised, the first group in the seven-unit code has to be MSS, while if the fifth signal element is a space, that group has to be SSM. This conversion is effected by energising the three modifying relays M1, M2, M3 in the way described above as determined by the conditions of the relay E. Also in this event, the first three relays A, B, C are arranged to connect battery at 36 through springs *a4*, *b4* and *c4* and their front contacts 37 in series to all the springs *f2*, *g2*, *h2* and *k2*, with the result that the one of the relays F, G, H, or K which is energised, applies battery at 36 to the segment S4, S5, S6 or S7 which is two segments removed from that which receives a mark from the spring *f3*, *g3*, *h3* or *k3* on the relay which is energised. To make this clear, if relay F is energised, its spring *f3* applies battery at 15 to the segment S4 but also through the circuit just described, battery at 36 is con-

nected through the spring *f2* and its front contact 38 to the conductor 39 and thence to segment S6 which is two segments removed from the segment S4. This is the necessary condition as can be seen from the second group in the seven-unit code in the fourth series as set out in Table 1.

Thus, all the conditions are fulfilled for providing conversions as set out in Table 1 for setting up the seven-unit error-detecting code signals at the transmitting segments S1 . . . S7, with a positive battery connection for each battery marking element and a free segment for each spacing element. These elements may conveniently be assumed to constitute the signals of one of a number of time-division channels in a multiplex telegraph system of the ordinary kind. The brush *Br1* which sweeps over the segments S1 . . . S7 sends the signals to the line L or through the conductor L, energises a line relay, as is necessary in sending double current signals.

The equipment for receiving the signals in the seven-unit error-detecting code and re-converting them into five-unit signals of the primary code is shown in Figure 2. The seven-unit signals are received by the line relay LR whose spring *lr* has marking and spacing contacts M, S, the former of which is connected to a brush *Br1* which sweeps over seven short segments RS1 . . . RS7, making contact in the middle of the respective periods of reception of the seven signal elements. Since each seven-unit signal contains three marks unless it has become mutilated, current is passed through the windings of three of seven receiving relays N, O, P, Q, R, S and T, each of which windings is connected to one of the segments RS1 . . . RS7. The three relays are energised in accordance with the particular signal being received by the line relay LR. The brush *Br1* is driven in synchronism with the received signals by any of the usual means. The relays N . . . T which are thus energised, are locked up through contact springs *n1* . . . *t1*, each of which is connected to battery and its front contact 40 and a brush *Br2* working over a long segment 41 in the circuits of the locking windings of the relays N . . . T which are energised so that these three relays are held locked until the operation of re-transmitting the five-unit signals formed in the receiver is completed, as will be described later.

When three of the relays N . . . T, neither more nor less, are thus energised, a circuit is completed through an error indicator or testing relay TR. The winding of that relay is connected to battery at 42 by a bank of contacts controlled by springs *n2*; *o2*, *o3*; *p2*, *p3*, *p4*; *q2*, *q3*, *q4*, *q5*; *r2*, *r3*, *r4*, *r5*; *s2*, *s3*, *s4*, and *t2*, *t3*. It will be seen that battery is connected to the spring *n2* whose back contact 43 and front contact 44 are connected respectively to the springs *o2* and *o3*. The front contact 45 of the spring *o2* and the back contact 46 of the spring *o3* are both connected to the spring *p3*; while the back contact 47 of the spring *o2* is connected to the spring *p2* and the front contact 48 of the spring *o3* is connected to the spring *p4*. The rest of the bank of contacts are connected forwards in a similar manner until at the end the spring *t2* has its front contact 49 and the spring *t3* has its back contact 50 both connected to the winding of the test relay TR, the other end of which is earthed. If the circuit through the bank of contacts is traced it will be found that there is a connection to the winding of the relay TR only when precisely three of the relays N . . . T are

energised. When as a result, the rest relay TR is energised, its spring *tr1* at its back contact *51* disconnects a connection *52* which leads to an error-indicator, while the spring *tr1* at its contact *53* applies battery to a number of relay springs and contacts which will be described in detail later. However, the battery connection to the spring *tr1* passes from battery at *54*, through a brush *Br3* and a segment *55*, which only come into contact when the three of the relays *N . . . T* in question have been locked.

When the test relay TR is thus energised, it connects battery at *54* through the contact *53*, inter alia to springs *n4*, *o5*, *p5* respectively of the relays *N*, *O* and *P*, through a conductor *56*. The springs *n4*, *o5*, and *p5* through their front contacts *57*, when energised continue the connection from battery at *54* and through back contacts *58* and springs *ma*, *mb*, *mc* of three modifying relays *Ma*, *Mb*, *Mc* and thence to the first three segments *59*, *60* and *61* of the five segments *59 . . . 63* of the retransmitting distributor. It will be recollected that in the case of a signal in the fourth series, as shown in Table 1, the second group of the signal in the seven-unit code is either MSMS or SMSM, so that in the former event, the fourth and sixth relays *Q* and *S* are energised and in the latter event the relays *R* and *T*. Certain springs of the relays viz. *q6*, *q7*; *r6*, *r7*; *s5*, *s6* and *t4*, *t5* are so interconnected that when the second group of a signal in the seven-unit code takes either of the above two forms and consequently the relays *Q* and *S* or *R* and *T* are energised, the three modifying relays *Ma*, *Mb*, *Mc* are operated and then the test relay TR, through its spring *tr1* and front contact *53* connects battery at *54* through the conductors *56* and *64* to the front contacts *65* of all three of the modifying relays *Ma*, *Mb*, *Mc* and also applies battery through the conductor *66* to the said bank of springs and contacts of the relays *Q . . . T*, in fact, at the back contact *67* of the spring *t4* and the front contact *68* of the spring *t5*.

The test relay TR also applies battery to springs *q8*, *r8*, *s7*, and *t6* of the relays *Q . . . T*. These springs *q8*, *r8*, *s7*, *t6* and the springs *q9*, *r9*, *s8* and *t7* of the same four relays and their contacts are so interconnected that whether only one of the receiving relays *Q . . . T* is operated, or whether two of those relays which are adjacent are operated, or whether three of those relays are operated, the result is that only one of four additional relays *W*, *X*, *Y* and *Z* is energised. For this purpose, the relay *Q* is regarded as following the relay *T*. The relay *W*, *X*, *Y* or *Z* which is operated is that corresponding to the first relay of the operated sequence of the relays *Q . . . T* when more than one of the latter are operated. The above result can be confirmed by checking the connections of the springs *q8*, *q9*, *r8*, *r9*, *s7*, *s8* and *t6*, *t7*. Thus, for example, if relay *Q* only of the four in question is energised the corresponding additional relay *W* will be energised from conductor *56* through conductor *69*, spring *t6*, its back contact *70*, conductor *71*, spring *q9*, its front contact *72*, winding of relay *W* to earth. Obviously the windings of the relays *X*, *Y* and *Z* have their circuits interrupted at the springs *r9*, *s8*, *t7* respectively. If, again, of the relays *Q . . . T*, the relays *Q* and *R* only are energised, the relay *W* is energised as before, the windings of relays *Y* and *Z* are interrupted at the springs *s8* and *t7* and although the spring *r9* makes contact, the circuit of relay *X* is now interrupted at the spring *q8*. As a final example,

if relays *Q*, *R* and *T* are energised and relay *S* is not energised, relay *Z* is energised, which is that corresponding to the relay *T* which is the first of the operated relays *T*, *Q* and *R* in the sequence as explained above. Actually, relay *Z* is energised from the conductor *69*, spring *s7* and its back contact *73*, spring *t7* and its front contact *74*, through the winding of relay *Z* to earth; the circuit of relay *W* is interrupted at the spring *t6*, the circuit of relay *X* is interrupted at the spring *q8* and the circuit of the relay *Y* is, of course, interrupted at the spring *s8* of the relay *S* which is not excited. These are typical examples and all other possibilities can be checked in a similar way.

Thus, in the first, second and third series of signals, the relays *W . . . Z* are operated to correspond to the second group of signal elements of the first series in the seven-unit error-detecting code. At the time referred to, the test relay TR has connected battery through conductors *56* and *75* to the spring *w1* of the relay *W*, and through conductors *56* and *76* to the spring *y* of relay *Y*, while the springs *x* and *z* of the relays *X* and *Z* are connected together; further the back contact *77* of the spring *w1* is connected to the back contact *78* of the spring *z*; the front contact *79* of the spring *w1* and the front contact *80* of the spring *y* are both directly connected to the fourth segment *62* of the transmitting commutator; the spring *w2* of the relay *W* is connected to the back contact *81* of the spring *y*, while the front contact *82* of the spring *w2* and the front contact *83* of the spring *x* are both connected to the fifth retransmitting segment *63*, through the back contact *84* and spring *mx* of an additional modifying relay *Mx*. As a result of these connections, the second group of the five-unit signals appears on the retransmitting segments *62* and *63* as MM, SM, MS or SS respectively, depending upon whether the additional relay *W*, *X*, *Y* or *Z* is operated. It can be seen from Table 1 above that this is the necessary condition for reproducing the second group of the signals in the five-unit code.

In the case of the fourth series of signals, from what has been stated above and from examination of Table 1, it will be realised that the relays *Q* and *S* or *R* and *T* are operated and cause the relays *W* and *Y* or *X* and *Z* to be energised. In either case, a connection is made from battery at *54* through the spring *tr1* and front contact *53* of the test relay TR and then through conductor *66* to the contacts *67* and *68* and then through the bank of springs *t4*, *t5*, *s5*, *s6*, *r6*, *r7*, *q6*, *q7*, by way of conductor *85* to the windings of the three modifying relays *Ma*, *Mb*, *Mc* all of which relays are, therefore, energised and apply marking elements to the segments *59*, *60* and *61* as already described. Furthermore, if only the relay *N* is energised, as happens in the fourth series when the first signal element of the seven-unit signal is a mark, a circuit is continued from the conductor *85* through the front contact *86* and spring *n3* of the relay *N* and conductor *87* to energise the additional modifying relay *Mx*. As a result battery is applied to the last retransmitting segment *63* from conductor *56* through conductor *88*, front contact *89* and spring *mx* of the relay *Mx* and this makes the fifth and last signal element of the retransmitted signal in the five-unit code a mark, as is required and shown in the fourth series in Table 1. With this arrangement, although the operation of the relays *W* and *Y* applies a marking element to the fourth

retransmitting segment 62 only, the fifth retransmitting segment 63 also receives a marking element, in the way just mentioned, when the first signal element of the seven-unit signal is a mark. This accounts for the first and third signals of the fourth series. When the relays X and Z are operated, no marking element is applied by their contacts to either of the retransmitting segments 62 and 63. However, in the way just explained, when the first signal element of a seven-unit signal is a mark, a marking element is applied to the retransmitting segment 63 by the additional modifying relay Mx and thus the second and fourth signals of the fourth series are formed.

The five retransmitting segments 59 . . . 63 may be used in conjunction with a preceding segment 90 and a following segment 91 to send on a standard five-unit signal together with a start and stop signal to the line L through the brush Br4 working over the segments 59 . . . 63. When the test relay TR is not energised, battery is applied through the back contact 51 and conductor 52 to an error-indicator in any convenient manner to print an error-indicating signal on the printer normally operated by the signals from the retransmitting segments 59 . . . 63.

One way of doing this is to make the printer employed selective to the signal consisting of five spaces which is not used in the standard five-unit code. Then the printer is arranged to print the error-indicating signal when this selection occurs. When the test relay TR is not operated, the five space signal is sent out by the brush Br4 because until the relay TR is energised, the battery at 54 is not connected to the relays. In such a case, the connection 52 and a separate error-indicating circuit is not required.

In some cases, it may be sufficient to indicate an error by inserting a letter space, that is to say, that whenever a mutilated character is received it appears as a space in which the correct character can be manually written in later; such a space signal can be retransmitted by providing a second spring tr2, shown in dotted lines, on the test relay TR, which spring has a back contact 92 connected by a conductor 92a to the third retransmitting segment 61.

There are three possible seven-unit signals in addition to the 32 shown in Table 1; they are:

SMSMSMS signal No. 33

SMSSMSM signal No. 34

MMMSSSS signal No. 35

The three signals, however, cannot readily be sent under control of five-unit perforated tape because only 32 different five unit signals are possible but these extra signals could be sent by providing switches for connecting the segments S1 . . . S1 in Figure 1 to alternative contact levers which may be controlled manually or otherwise according to requirements. The above signal No. 33 or No. 34 may, for example, be used to give instructions to the sending operator of the return circuit, being sent once, twice or another number of times to convey different meanings such as "stop," "go ahead" or "repeat last message." The signal may cause a bell to ring.

Thus, as each of the above signals Nos. 33 and 34 has a mark as its second element, the spring o4 of the relay O may connect the conductor 93 through a front contact 94 to a cut-off relay COR, the circuit being from battery at 54, brush Br3, segment 55, spring tr1, contact 53, conductor 66 and through springs t4 or t5, s5 or s6,

r6 or r7, q6 or q7, conductor 85, conductor 93 and contacts 94, o4 and the winding of relay COR. The relay COR at its spring cor2 and back contact 95 cuts off the five-unit output from the brush Br4 to the line L and at its front contact 96, connects battery to line to give the "stop" signal. The relay also at spring cor1 and front contact 97 connects battery to a bell 98 or other convenient indicator. By connecting battery at contact 96 to the line L, the stop signal is prolonged and continuous running of the printer avoided. Clearly, however, it would be possible to provide the relay COR with a single spring which could cut off the output from the brush Br4 to the line L and to connect that output to a connection to the bell or other indicator. For that purpose a conductor 99 from the brush Br4 would be connected to the spring of the relay COR, the back contact of the spring being connected to line L and its front contact to the bell or other indicator circuit.

If it is desired to use the above two signals No. 33 and No. 34 individually, the springs q6, q7, r6, r7, s5, s6, t4, t5 and their contacts would have 25 to be separated and would be arranged to control separate cut-off relays each providing one of these two signals in a way which is thought to be obvious. If it is desired to utilise the above signal No. 35, it may be received by connecting another 30 cut-off relay, as shown in Figure 2, at COR2, to the spring q5 of the relay Q. Since the first three elements of signal No. 35 are marks, there is a circuit from battery at 42 through spring n2, its front contact 44, spring o3 and its front contact 43, spring p4 and its front contact 100 and conductor 101 to the winding of the relay COR2. The latter, when energised, maintains the battery connection to the line L through its spring 102 and front contact 102a connected to battery. An 40 additional contact spring (not shown) on the relay COR2 would be used to operate a bell or perform any other function desired.

In the transmitting system shown in Figure 3 in which signals are transmitted in an eight-unit error-detecting code derived from perforated 45 tape perforated with the signals of six-unit primary code, the circuits are simplified with respect to Figure 1 by the use of a number of contact rectifiers. However, as before, the perforated tape controls the operation of six peckers Pa, Pb, Pc, Pd, Pe and Pl; each mark in a signal causes the corresponding pecker Pa . . . Pl to close its contacts 1, 2 and, as before, to connect battery at 3 to the actuating 50 winding of the corresponding relay A, B, C, D, E and L to earth at 4. Also each of these relays on being actuated closes the circuit of a locking winding battery at 6 through spring a1 . . . 11 and its front contact 5 to a continuous segment 60 7 and through a brush Br2 to earth at 8. The peckers pass through the perforations in the tape for a suitable period for example, that represented by X in Figure 3.

The conversion of the signals is set out in Table 65 2 above from which it will be noted that the first group of each signal in both codes is the same and contains four signal elements. In the first, second and third series, this first group contains 68 respectively three, two and one mark so that for 70 these three series of signals, three, two and one of the relays A . . . D are energised. For any of these signals, battery at 104 is connected to a point 105 through one of three rectifiers R1, R2 and R3. Details of the connections are as follows: In the first series where there are three

marks in the first group, it will be seen that owing to the connections of the spring a_2 of relay A, springs b_2 and b_3 of relay B, spring c_2 , c_3 , and c_4 of relay C and springs d_2 , d_3 , d_4 and d_5 of relay D, the battery at 104 is connected to a point 106 which can be checked by tracing the circuit when any three of the relays A, B, C and D are energised; it will also be seen that battery at 104 is connected to a point 107 when any two of the relays A, B, C and D are energised and, finally, when only one of those relays is energised, battery is connected to the point 108. The point 105 is connected by a conductor 109 to further springs a_3 , b_4 , c_5 and d_6 of the relays A, B, C and D so that under any of these conditions, these springs are connected to battery at 104; thus if any one or more of the relays A, B, C and D are energised when the signal contains mark elements in the respective positions according to the first three series of signals in Table 2, those marks are applied to the distributor segments S1, S2, S3 or S4.

For the fourth series of signals according to Table 2 above, it will be noted that there are no marking units in the first group and then battery at 104 is connected through the springs of relays A, B, C and D already mentioned, to the point 110 and thence through a rectifier R4 to the distributing segment S2, thus giving a mark as the second signal element in the first group of the eight-unit signal. It will be observed from Table 2, however, that it is desired to have a mark as the third or fourth element depending on whether the last signal element in the six-unit primary code is a mark or a space. To produce this result, the relay L has a spring l_3 with a back contact 111 connected directly to the transmitting segment S3 and a front contact 112 connected directly to the transmitting segment S4. In the fourth series, the first four units of a signal in the primary code are spaces so that the relays A, B, C and D are all de-energised and, as already explained, under those conditions there is a connection from battery at 104 to the point 110 and this connection continues through another rectifier R5 to the spring l_3 . Consequently, when the last unit of a signal in the fourth series is a mark and the relay L therefore energised, this battery connection is continued through the spring l_3 and contact 112 to the segment S4 which thus receives a mark as is required. Also, if the last unit in the signal in the primary 6 unit code is a space, so that the relay L is not energised, the battery connection passes on through the back contact 111 to the distributor segment S3, resulting in the third unit being a mark in the eight-unit signal which, of course, agrees with Table 2. For this series of signals, as there are no marking units in the first four units, the relays A, B, C, D are all de-energised so that none of the springs a_3 , b_4 , c_5 and d_6 closes its contact.

In the fifth series of signals, the first group always consists of four marking units which means that the four relays A, B, C, D are all energised with the result that battery at 104 is connected through the spring a_2 , its front contact, the spring b_3 and its front contact, the spring c_4 and its front contact and the spring d_5 and its front contact to a point 113 from which it is carried on through another rectifier R6 to the first distributor segment S1. It can be seen from Table 2 that in the fifth series in the eight-unit code, either the third or fourth unit has to be a mark, depending upon whether the last unit

of the six-unit signal is a space or a mark; thus battery is also connected to the segment S3 or S4 to produce this result, as described above for the fourth series, except that now, battery is connected to the spring l_3 from the point 113 through a further rectifier R7.

The second group of units in the six-unit primary code is converted into the second group in the eight-unit error-detecting code in a manner similar to that described with reference to Table 1 and Figure 1 for by comparison of Tables 1 and 2 it will be seen that the conversion is precisely the same in the two cases. In the present instance, however, the second mark unit to be added 10 for signals in the second and third series, as compared with signals in the first series, is introduced through the point 108 or the point 107 which are respectively connected to a point 114 through further rectifiers R8 and R9. For this purpose 15 the four additional relays F, G, H and K are connected exactly as in Figure 1 so as to be controlled by the springs e_2 and e_3 of the relay E and by the spring l_2 of the relay L. The springs f_1 , f_2 , and f_3 of the relay F, the springs g_1 , g_2 and g_3 of the relay G, the springs h_1 , h_2 and h_3 of the relay H, and the springs k_1 , k_2 and k_3 of the relay K are connected to one another exactly as in Figure 1 and to the distributor segments S5, S6, S7 and S8 instead of segments S4, S5, S6 and S7, of course. The point 114 is connected to the springs f_1 , g_1 , h_1 and k_1 corresponding precisely to the similar connection in Figure 1.

In the third series of signals, the third mark unit has to be added as seen from Table 2, by 35 way of the point 110 through another rectifier R10, to the point 115. A mark corresponding to this third mark is added in the same way for signals in the fourth and fifth series but without the second mark; it is added by way of connections from points 108, and 113 through rectifiers R11 and R12 to 115.

A suitable receiving system for the signals produced as described with reference to Figure 3 is illustrated in Figure 4. The eight-unit signals are received by the line relay LR as in Figure 2 and, indeed, the system is similar to that shown in Figure 2 except that there is a certain amount of simplification obtained by the use of rectifiers. The spring l_7 of the line relay LR has a front marking contact M and a back spacing contact S and, as in Figure 2, the marking contact M is connected to a brush Br_1 which sweeps over eight short segments $SR_1 \dots SR_8$, making contact with them in the middle of the respective periods of reception of the eight signal elements.

Since each eight-unit signal contains four marks unless it has been mutilated, current is passed through the windings of four of eight receiving relays N, O, P, Q, R, S, T and U, the winding of each relay being connected to one of the segments $RS_1 \dots RS_8$ and to earth. Thus the four relays are energised by the line relay LR in accordance with the number of marks in the received signals with which the brush Br_1 is driven in synchronism by any of the usual means. The four relays thus energised are locked up through contact springs $n_1 \dots u_1$ each of which is connected to battery and through its front contact 40 and a brush Br_2 which is earthed and works over a long segment 41 so that the four relays which have been energised are held locked until the operation of re-transmitting the six-unit signals in the primary code is completed.

When there are thus four marks in the re-

15

ceived eight-unit signal, neither more nor less, a circuit is completed through the test relay TR. The winding of that relay is connected to battery at 42 by a bank of contacts controlled by springs n_2 ; o_2 , o_3 ; p_2 , p_3 , p_4 ; q_2 , q_3 , q_4 , q_5 ; r_2 , r_3 , r_4 , r_5 , r_6 ; s_2 , s_3 , s_4 , s_5 ; t_2 , t_3 , t_4 and u_2 and u_3 . This bank of springs is similar to that provided in Figure 2 but is modified to suit the eight-unit signals and, consequently, it is not necessary to describe these contacts in greater detail although it can be seen by tracing the circuits that battery is connected to the winding of relay TR only when exactly four of the relays N . . . U are energised. Again, when the test relay TR is energised in this way, its spring tr and its back contact 51 disconnects a connection 52 which leads to the circuit of an error-indicator. Connection is made to battery at 54 through brush Br_3 and a segment 55 but contact is only made when the four of the relays N . . . U in question have been locked.

When the test relay TR is thus energised, it connects battery at 54 through its front contact 53 by way of a conductor 56 inter alia to springs n_6 , o_5 , p_5 and q_7 . These springs, through their front contacts 57, when energised continue the connection from battery to the first four segments 116, 117, 118 and 119 of the six segments 116 . . . 121 of the retransmitting distributor.

The conversion of the last four units of the eight-unit signal into the last two units of the six-unit signal in the primary code is effected in a manner similar to that described with reference to Figure 2 except that in the case of signals in the fourth and fifth series, marking is applied to the sixth retransmitting segment 121 through the contact spring q_6 and a rectifier R14 for which purpose the springs r_1 , r_8 ; s_6 , s_7 ; t_5 , t_6 and u_4 and u_5 are connected and operated in the same way as the respective four pairs of springs in Figure 2.

In the case of signals in the first, second and third series, the units in the first group of the received eight-unit signals are repeated or passed on without change to the retransmitting segments 116, 117, 118 and 119 by the contact springs n_6 , o_5 , p_5 and q_7 . The battery connection to the springs o_5 , p_5 and q_7 from the conductor 56 passes through the spring y and back contact 122 of an additional relay Y which is de-energised by the spring n_5 of the relay N when the first unit of the received signal is a mark.

However, in the case of signals of the fourth series, the relay Y is operated because, as can be seen from Table 2, in that series, the first unit of a signal in the eight-unit code is a space and therefore the spring n_5 rests on its back contact 123 and as the second group of the eight-unit signals in that series is either MSMS or SMSM, battery is connected through conductor 66 and the springs u_4 , u_5 ; t_5 , t_6 ; s_6 , s_7 ; and r_7 , r_8 , to the conductor 85 and winding of relay Y. As a result, battery from conductor 56 is cut off from the springs o_5 , p_5 and q_7 at the back contact 122 of relay Y and, since the connection to the first segment 116 is interrupted between the spring n_6 and its front contact 57, the four retransmitting segments 116, 117, 118 and 119 all receive spaces which, of course, agrees with the first column in Table 2 above.

In the 5th series of signals, the first unit of the received eight-unit signal is always a mark so that the relay N is energised and as the conductor 85 is connected to battery for all these signals for

16

the reason mentioned above, the spring n_5 at its front contact 124 applies marking to the segments 117, 118 and 119 through rectifiers R15, R16, R17 respectively and the first segment 116 receives a mark through the spring n_6 and its front contact 57 so that the first four units are all marks in agreement with Table 2.

There are six possible eight-unit signals in addition to the 64 shown in Table 2; they are:

10	MMMM	SSSS	signal No. 65
	SSSS	MMMM	signal No. 66
	MMSS	MSMS	signal No. 67
	MMSS	SMSM	signal No. 68
15	SSMM	MSMS	signal No. 69
	SSMM	SMSM	signal No. 70

As explained in connection with Figure 2, these signals cannot readily be sent under control of six-unit perforated tape because only 64 different six-unit signals are possible. However, in Figure 4, two cut-off relays COA and COB are provided which are arranged to be operated only by signals Nos. 67 and 68 and Nos. 69 and 70 respectively. Thus signals 67 and 68 both have their first two units as marks so that relays N and O are both energised. It will be recollect that because of the form of the second group of these two signals, there will be a connection from battery to the conductor 85 and this connection is continued through the spring o_4 of relay O and its front contact 125 and the front contact 126 of the spring n_4 of the relay N to the winding of relay COA and to earth, so that as already stated, the relay COA is then energised. In a similar way, for signals 69 and 70, the first two units are spaces so that the relays N and O are not energised. Thus, under these conditions, the connection to battery at conductor 85 is continued through the spring o_4 , its back contact 127 and through the back contact 128 and its spring n_3 to the winding of relay COB and to earth so that now the relay COB is energised. As illustrated, the signals 67 and 68 are sent by connecting battery at 129 by means of the spring coa_2 to the conductor 130 and the signals 69 and 70 are sent by connecting battery at 131 to the spring co_2 and conductor 132. When either of these two relays is operated, the normal output in the six-unit primary code to the line L is cut off, either at the back contact of spring coa_1 or the back contact of spring co_1 and either of those springs at its front contact 133 or 134, connects battery to the line L providing the stop signal for the printer. Any one of these four signals may be used to signal any special function, such as has already been described with reference to Figure 2.

In the two transmitting and receiving systems described as examples, generally speaking, the necessary connections have been made and interrupted by relays and their contact springs but these may be replaced by any recognised equivalent devices for producing the same effects such as thermionic valves which are rendered conductive and non-conductive under desired conditions.

I claim:

1. A telegraph system arranged to transmit signals in an error-detecting code all the signals of which consist of the same number of marking and the same number of spacing units, comprising transmitting apparatus arranged to convert signals in a primary equal-length code into signals in said equal-length error-detecting code, said second-mentioned signals consisting of a greater number of units than the signals in said primary code, said transmitting apparatus comprising

means for passing forward and transmitting one group of units in each of at least the majority of the signals in said primary code, as a group of units in said error-detecting code which is the same in marking and spacing permutation as the group in said primary code and means for modifying a second group of units in each signal in said primary code and converting same into a group in said error-detecting code determined by the permutations of both groups of the respective signal in said primary code.

2. A telegraph system according to claim 1, in which said modifying means convert a second group in each signal in said primary code containing only two units thus providing four permutations, into groups of units in said error-detecting code containing the necessary marking units to make up the predetermined number of marking units in each signal in said error-detecting code in consideration of the number of marking units in the first group of each signal in said error-detecting code.

3. A telegraph system according to claim 2, in which said transmitting apparatus comprises means for producing signals in said error-detecting code in a number of series, according to which said second groups of units in the signals contain a single marking unit in successive positions, contain a second marking unit in the position following the first marking unit and also contain a third marking unit in the position following the second marking unit respectively.

4. A telegraph system according to claim 1, comprising relays controlled in accordance with the signal units in said primary code and a transmitting commutator connected to said relays so as to receive the first group of units of signals in said primary code unchanged at least for the majority of the signals.

5. A telegraph system according to claim 4, comprising means for transmitting an additional series of signals in said primary code and means for converting the first group of each of said additional signals into a form depending upon whether the last unit of each said signals in the primary code is a marking or a spacing unit and comprising modifying relays controlled by contacts of said relay which is controlled in accord-

ance with the last unit of the signal in said primary code.

6. A telegraph system according to claim 5, comprising transmitting apparatus arranged to convert a second group of signal units in said primary code each consisting of two units, into groups each consisting of four units in said error-detecting code, said two relays controlled in accordance with the units of the second groups of units in said primary code being arranged to control four additional relays connected to apply the second group of units in said error-detecting code to the segments of said transmitting commutator.

15 7. A telegraph system according to claim 1, comprising receiving apparatus for handling the received signals in said error-detecting code and comprising means for passing on, at least for the majority of signals in said error-detecting code, the first group of signal units unchanged but for reconverting the second group of units in each of said signals into a second group of signal units in the original form in said primary code.

25 8. A telegraph system according to claim 7, comprising receiving relays with means for applying the signal units in said error-detecting code to said receiving relays in succession, said relays having a bank of interconnected contacts, a testing relay so connected to said bank of contacts that when a received signal contains the predetermined number of marking units, no more and no less, said testing relay is energised through said bank of contacts and only when energised, allows the incoming signal to be set up by connecting battery to the appropriate relay contacts 30 after said receiving relays have all been influenced by said incoming signal units.

35 9. A telegraph system according to claim 7, comprising receiving relays connected so as to be responsive to the respective units of the incoming signals in said error-detecting code, and a set of additional relays connected to set up the second group of signal units as reconverted into said primary code and also connected to said receiving relays corresponding to the signal units 40 in the second group so as to be controlled thereby.

45 HARRY VERNON HIGGITT.
